PORTABLE INDICATING HOLDERS AND SETTABLE INDICATORS THEREFOR

Robert Gourdon, Paris, France, assignor to Societe Anonyme dite: Centre d'Etudes M. B. A. (Mecanique Ballestique, Armentement), Paris, France

Application October 20, 1951, Serial No. 252,383

Claims priority, application France January 16, 1946

24 Claims. (Cl. 214—11)

My invention relates to holders or containers having settable indicating devices. The particular holders disclosed herein are intended especially for use in apparatus for sorting articles, particularly mail.

The present application is a continuation-in-part of my copending applications for United States patents Serial No. 722,198, filed January 15, 1947, for Holders With Adjustable Identifying Codes and Arrangements Relating Thereto, now abandoned; Serial No. 765,946, filed August 4, 1947, for Apparatus for Sorting Articles Such as Mail, now Patent No. 2,669,365 and Serial No. 17,984, filed March 30, 1948, for Methods and Means for the Sorting and Classification of Documents or Articles, now Patent No. 2,696,919. Various features of apparatus for sorting articles, utilizing the holders described herein, are disclosed in said applications, in my copending application Serial No. 722,197, filed January 15, 1947, for Apparatus for Indexing Articles, now abandoned, in my Patent No. 2,469,035, dated May 3, 1949, for Electro-mechanical Device for Governing Predetermined Changes of Positions, and in my application Serial No. 300,160 filed July 22, 1952, which application is a continuation-in-part of certain of the earlier applications.

The present invention comprises a receptacle or holder having one or more indicating elements which are selectively and individually settable in different indicating positions. The holder illustrated is especially designed for use in sorting or classifying apparatus. When so used, an article to be classified is placed in the receptacle and one or more of the indicating elements are set to indicate, by an established code, those characteristics of the article on which the classification is to be based. The holder containing the article is then moved through a conveyor system which includes multiple paths of travel leading to a number of receiving bins. The conveyor system includes mechanism which senses the code indicated by the elements on the holder and directs the holder along a particular path of travel corresponding to the indicated code. When the holder reaches the proper bin, it is unloaded.

In my previously mentioned copending applications, there is described a method and apparatus for sorting mail. When the present invention is used in such apparatus, a letter or other piece of mail is placed in each holder and the indicating elements of the holder are set to indicate, according to the code, the destination of the letter. The holders then travel through the conveyor system along paths determined by the code setting of the indicating elements, so that all letters intended for the same destination are deposited in the same bin.

An object of the present invention is to provide a holder of the type described including improved settable indicating means which is shielded against disturbance by contact with external objects.

A further object is to provide a holder of the type described including improved indicating means which is visible or otherwise observable from the outside, even when the holder is stacked with a number of other holders.

Another object is to provide an improved holder which may be stacked with other holders so that all holders in the stack may have articles inserted therein or discharged therefrom without the holder being taken from the stack.

A further object is to provide a holder having an open-

2

able and closable discharge opening and improved means for operating the same.

A further object is to provide an improved settable indicator. A further object is to provide a settable indicator which is shielded against contact with external objects but which may be readily observed. A further object is to provide an indicator including a settable indicator element which may be sensed by a mechanical device without disturbing its indicating setting.

10 The foregoing and other objects of the invention are obtained by providing a holder having wide front and rear walls joined by narrow side walls to form a pocket. The rear wall is longer than the others so as to form upper and lower projecting flanges. The lower flange serves as a support for the holder and both flanges are adapted to cooperate with guiding slots provided in a supporting structure. The top of the pocket is open and the bottom is movable so that it may be opened and closed. The opening mechanism includes a pair of rods whose lower ends engage the movable bottom. These rods extend upwardly through the pocket with their upper ends accessible at the open top.

15 Each of the thickened side walls is provided in its outer surface with a number of open recesses. Indicating elements are housed in said recesses and are settable in at least two different positions. These elements may be observed from the exterior of the holder in at least some of their indicating positions.

20 The recesses may be located in any side of a holder. 25 Where the holders are adapted to be stacked, as are the relatively thin, flat mail holders described herein, it is advantageous to locate the recesses in the side walls, i. e., the walls which are exposed when the holders are stacked. Such a construction permits the simultaneous inspection 30 of a set of stacked holders, without any necessity for handling each holder separately to observe its indicating elements.

35 The indicating elements may be of any suitable form, for example, cylinders, balls, or plates. Such elements are constructed so that they always remain within their recesses, in order to prevent disturbance of the settings of the elements and to permit easier handling of the holders. The externally visible parts of the indicating elements may carry indicating marks, either visual (for example, alphabetical, numerical, or colored signs) or constructed so that they be sensed by mechanical contact (for example, ribs or grooves), or by other known means (for example, magnetization, electric charges, etc.).

40 The several positions of the indicating elements in the recesses may include a neutral position and one or more active positions. In the neutral position, the indicating element is either absent, retracted or arranged so as to offer either no indication or a neutral indication to the eye or to an identifying feeler. In each active position, the element shows a mark forming a part of an 45 identifying code, which code is registered on the holder by means of one or more code indicating elements. This code may be observed visually or by suitable mechanical or other apparatus capable of sensing a physical condition of an indicating element as outlined above.

50 The indicating elements may be held in their selected settings by spring means. In certain embodiments of the invention, these spring means bias the indicating elements to bring ribs formed thereon into registry with notches or slots on the front edges of the recesses, there- 55 by locking the elements in place.

55 In the preferred embodiment of the invention, the indicating elements may be reset only by a double change of position, for instance, by a translatory motion followed by a rotary movement, which reduces the possibility of accidental movement of said elements.

60 Each of the several indicating elements is individually set in a code indicating position. The elements may be

set either successively or simultaneously. Such a setting is hereinafter referred to as a coding operation. The resetting of the elements to their neutral positions, hereinafter referred to as the decoding operation, may also be effected either separately or simultaneously.

In some embodiments of the invention, the recesses containing the indicating elements are provided with one opening through which the coding and decoding operations are carried out and a second opening used only for identifying the code. In other embodiments, the coding, decoding and code sensing or identifying operations are all performed through the same opening.

The foregoing and other features of the invention are presented in detail in the following description, considered with reference to the accompanying drawings, which illustrate several embodiments of the holders and the code indicating devices relating thereto. In the various figures of the drawings, the same reference numerals denote corresponding parts.

of code indicating mechanism, taken on the line XXV—XXV of Fig. 26.

Fig. 26 is a horizontal sectional view of the mechanism of Fig. 25.

Fig. 27 is a perspective view of a detail of the mechanism of Figs. 25 and 26.

The holder illustrated in Figs. 1 to 3, is constructed in the shape of a pocket, open at its upper end and comprising a front wall 1, a rear wall 2 and two thickened side walls 3. Outer and inner reinforcing plates 4 and 5 are shown on the side walls 3.

The pocket has a bottom flap 6, shown in this modification as a plate riveted on the lower part of the wall 1 and sufficiently flexible so that it may be opened to the position shown by dotted lines in Fig. 2. When the flap is opened, the holder pocket is emptied by gravity.

The bottom flap 6 is self-biased to its closed position shown in full lines in Fig. 2, in which position it engages the rear wall 2. It may be opened by means of a pair of rods 7 which extend downwardly through suitable guides in the pocket, and have their lower ends engaging the flap 6. The upper ends of the rods 7 are accessible through the open top of the pocket and are provided with flanges 7a to facilitate lifting of the rods after they have been depressed to open the flap 6. The flap 6 is thereby maintained open until the rods 7 are positively moved upwardly. This upward movement of rods 7 may readily be accomplished with the aid of the flanges 7a, either manually or with a suitable mechanical device for engaging and lifting those flanges.

The rear wall 2 is longer vertically than the front wall, 35 so as to provide upper and lower extending flanges. The lower flange serves as a support for the holder, while both flanges are adapted to engage slots in a supporting structure so that the holder is held vertical. The upper flange is provided with a central notch 2a and the lower flange with end notches 2b. These notches may be engaged by supporting or guiding rails so as to maintain a stack of holders in alignment.

In the modification illustrated in Figs. 4, 5 and 6, the front wall 8 of the pocket has an integral extension 8a. 45 This extension is flexible and is normally bent inwardly to form the bottom of the pocket as shown in Fig. 5. The front wall 8 is also provided with integral side flanges 8b, which take the place of the reinforcing plates 4 of Figs. 1 and 2. The edge of front wall 8 is fastened to 50 the back wall 2 by crimping, as indicated at 9 in Fig. 6.

Another modified form of openable bottom for the pocket is shown in Figs. 7 and 8. There the pocket bottom is formed by a rigid curved plate 10, mounted on the front wall 1 by means of spring hinges 11.

55 Other modifications of the bottom wall obviously might be designed. In certain cases, this wall may be fixed if the pocket is to be emptied by turning it upside down.

In order to make it easier to grip the holder by mechanical means for moving it laterally, four pieces 12 (Fig. 1) in the shape of flat inwardly opening hooks are attached to the upper and lower ends of the side walls 3. These hooks facilitate endwise movement of the holder, either manually or by a mechanical device. The side walls 3 are each provided with a number of recesses 13 (Figs. 10 and 11). The reinforcing plates 4 of Figs. 1 to 3 and the side flanges 8b of Figs. 4 and 6 are provided with openings 14 aligned with the recesses 13. An indicating element 15 is located in each of these recesses.

Each indicating element 15 comprises a cylindrical body with a conical rear end 15a and a diametrical rib 15b on its front end. The rib 15b has widened tips 15c.

The recesses 13 are generally of the same form as the elements 15. Each recess 13 has a cylindrical portion 13a which receives the body of the element 15 and is slightly larger so that the body is rotatable therein and

translatable to a limited extent. The outer end of this cylindrical portion 13a terminates at a tapered shoulder 13b leading to another cylindrical portion 13c of enlarged diameter. The tips 15c are rotatable and translatable in the portion 13c. Engagement of tips 15c with shoulder 13b limits the inward movement of the element 15.

The edge of plate 4 around each opening 14 is bent inwardly to form a frusto-conical portion 14a, and notches 14b are cut therein (see Figs. 10 and 11). These notches are provided in diametrically opposed pairs.

Each indicating element 15 is biased toward the outer end of the recess by a flexible leaf spring 16 which is shown as being formed from the inner reinforcing plate 5 by a stamping and cutting operation. The conical end 15a of the indicating element projects into an opening 16a formed in the leaf spring 16. When the rib 15 is aligned with a pair of notches 14b, the leaf spring 16 holds the rib in the notches and angular movement of the element 15 is thereby prevented.

In order to change an element from one angular position to another, it is necessary to push it inwardly in opposition to the leaf spring 16 so as to release it from the two notches with which it has been engaged, and then to turn it while holding it inwardly. If the element 15 is turned to bring the rib 15b into alignment with another pair of notches and then released, the leaf spring 16 again forces the rib forward into the new pair of notches, thereby retaining the element in a new angular position. It is manifest that it is almost impossible for any accidental impact or vibration to produce a combination of forces that would be capable of translating and rotating an indicating element to change its indicating position once it has been set in the notches 14b. Furthermore, since the element 15 is always held securely completely within the recess 13, it cannot readily come into contact with any external object which might accidentally change its position. The inwardly bent portion 14a of the plate 4 blocks the outer end of the recess 13 sufficiently to prevent movement of the element out of the recess and to protect the element against accidental contacts with external objects.

There is shown in Fig. 12A the operating end of a tool 17 which may be used either for setting the indicating element from one angular position to another or for sensing the position of the element. When used as a setting tool, the end of the tool is inserted through the aperture 14 so that the slot 17a in the end of the tool receives the rib 15b on the outer end of the indicating element. As the tool 17 is pushed farther in, the flat end of the tool engages the flat surfaces on the end of the main body of the indicating element. The element may then be pushed in against the spring 16 until the tips 15c are disengaged from the notches 14b. The element 15 may then be rotated by simply turning the tool, while holding the element pressed inwardly against the spring 16. When the element has been turned to the desired new angular position, the tool may be released and the spring 16 then moves the tips 15c outwardly into the new notches 14b.

It is not necessary to have the slot 17a aligned with the rib 15b before the tool is inserted to engage the indicating element. If the tool slot is not so aligned, then the flat end of the tool engages the outer end of the rib and if the tool is then rotated, its flat end slides over the end of the rib until the slot is aligned with the rib, whereupon the rib enters the slot. The element does not rotate until the rib enters the slot, even though the tips 15c have been pushed in, free of the notches 14b, because the flat end of the tool cannot apply to the element sufficient torque to overcome the friction between the element and the spring 16.

When the tool 17 is used as a sensing tool, it is first turned to a predetermined angular position, corresponding to one of the four possible positions of the indicating

element 15. The end of the tool is then pushed inwardly against the element 15 which is to be checked. If the angular position of the element 15 corresponds with that of the tool 17, then the tool 17 can move inwardly until its flat end engages the flat surfaces on the end of the body of element 15, and can then move the element further against the spring 16 until the tips 15c engage the shoulder 13b. However, if the angular positions of the rib 15b and the slot 17a do not correspond, then the flat end of the tool 17 engages the end of the rib 15b, and when the inward travel of the element 15 is stopped by the shoulder 13b, the tool 17 is in a different position (farther out of the recess) than in the case where the slot and the rib are in angular correspondence. By using a simple inward thrusting movement of the tool 17, it is possible to check whether or not the angular position of the indicating element corresponds to that of the slot in the tool. The difference in the travel of the tool under the two different conditions may be used to operate an indicator or to perform a control function.

The positions of the indicating elements are observable from outside the holder, either by visual inspection or by the use of sensing tools such as the tool 17. It should be noted that the observation of these elements can be carried out either one element at a time or all elements simultaneously. When carried out simultaneously, a number of tools must be used, corresponding to the number of elements. Furthermore, these sensing or identifying operations can be performed when the holders are stacked, since the indicating elements are located in the side walls of the holders, which side walls are accessible when the holders are stacked.

Each indicating element has four different indicating positions, shown at A, B, C, D in Fig. 13. Each element by itself is capable of giving four indications, each having a meaning established by any arbitrarily selected code. If two elements are used together, there are sixteen possible combinations of elements and therefore sixteen different code indications. Eleven elements, as shown in Fig. 1, can give a number of indications equal to $(4)^{11}$, or 4,194,304.

When these holders are used, for example, in a mail sorting system, it is possible that a simple system might only require four classifications, and it would then be only necessary to use one indicating element on each holder. In a very complex sorting system, there may be thousands of classifications. In such a system, a combination of indicating element positions for each classification would be established by the code.

It would be possible to use one group of two or three elements to establish a state classification, another group to establish a city classification, and so forth.

Since indicating elements are provided on both ends of the holder, it is possible to have the holder indicating elements set or coded at both ends. In that event, a sensing device adjacent one end of the holder can check it for one code while another sensing device at the opposite end of the holder checks it for a different code at the same time.

In a complex system, several successive sensing or identifying operations may be required. It is therefore essential that the position of the indicating element should not be disturbed by the sensing operation. The structure described above meets this requirement, since the sensing operation is a linear movement of the sensing tool, while a change in position of the element requires a linear movement followed by a rotary movement.

Two minor modifications of the form of indicating element shown in Figs. 9-12 are illustrated in Figs. 15-18. In these forms, the tips 15c of Figs. 9-12 are replaced, insofar as their function of limiting the inward travel of the element is concerned, by a disc of greater diameter than the body of the element. In Figs. 15 and 16, the disc is shown at 22 and is polygonal, while in Figs. 17 and 18 the corresponding disc 23 is circular. In both cases,

it forms an extension of a cylindrical body 24 having a conically tapered rear end 24a; the code mark on the front face of the element may be formed either by a rib, or by a diametrical groove 26, as shown. When a groove is used, the cutting-out of the edge 14a of opening 14 is reversed, the notches 14b being replaced by projections or teeth; the general shape of the recess 13 may remain unaltered.

Various modifications of indicating elements will now be described, which are suitable for use in installations where only two indicating positions for each indicating element are required. These modifications also illustrate mechanism for effecting the return to normal of the indicating elements in all recesses.

In the modification illustrated in Figs. 19 to 21, each of several recesses 27 houses a pair of jaws 28 and 29 pivoted respectively on pivot pins 30 and 21, and biased toward each other by means of a U-shaped leaf spring 33. Near its front end, each jaw has a projection or tooth 34 or 35. On the inside of side flange 8b, between each pair of recesses 27, is attached, for instance by rivets, a plate 36 (Fig. 21), having its ends cut narrow to form yieldable tongues 37.

The jaws serve as indicating devices, and are movable between open and closed positions. The spring 33 biases the jaws toward their closed positions. They are settable in their open positions by insertion of a plunger 38, as shown in the lower part of Fig. 19, so as to spread jaws 28 and 29 and force the tongues 37 outwardly until the ends of the jaws enter into openings 37a formed in the tongues. The tongues 37, being yieldable, return to their original positions and abut against the projections 34 and 35, when the punch 38 is withdrawn. The spring 33 biases the jaws toward each other.

The sensing or observation of the code setting may be carried out either by plungers similar to 38 but of smaller diameter, operating through the same aperture. Alternatively, plungers 39 (Fig. 20) may be used, operating through openings 39a in the front wall of the holder. If a plunger 39 can come into the position shown in dotted lines in Fig. 20, then the jaws are in their open position. If the plunger 39 is stopped before it reaches the dotted line position, it shows that the jaws are pressed against each other in closed position. The sensing operation through the side opening 39a is to be preferred, because then the sensing tool has no tendency to change the position of the indicating elements.

All the indicating devices may be returned to closed position by means of a rod 40, extending vertically through the wall 3, and carrying several spring fingers 41, one in each recess. If the rod 40 is moved downwardly from the position shown in Fig. 19, the fingers 41 engage first the upper tongues 37 and then the lower ones, forcing them outwardly so as to disengage the end of each jaw from its associated opening 37a. The jaws shut again. The motion of the rod 40 has no action on those jaws which have remained closed. The jaws 28 and 29 may be observed visually through either the front aperture or the side aperture 39a when they are in their closed positions, but are not readily visible when they are open.

In the modification illustrated in Figs. 22, 23 and 24, each recess 21 contains a housing formed by two yieldable plates 42 and 43 having two sets of opposed concave recesses to provide two positions for a ball 44, which serves as an indicating element. The normal or neutral position of this ball is that shown in dotted lines in Fig. 22 nearest the opening 14 of the reinforcing plate 4. A plunger 45, shown in Fig. 22 on the outside of the holder, may be used to move the ball from the neutral position to the active one. A feeler 47 (Fig. 23) may then check the position of the ball for each recess, either through a lateral opening 46, or through the opening 14 itself. As in the case of the arrangement of Figs. 19 to 21, the sensing or checking through the lateral opening 46 is preferred, because the sensing tool then has no tendency to change the indicating position of the elements.

A device is provided for setting all the balls to their neutral positions. This device includes a vertically movable rod 48, housed in the wall of the pocket and provided with a cam 49 for each recess. When this rod is pressed down, the cam surfaces 49 pass through slots in the plates 42 and 43, engaging any balls which be in their rearward positions and forcing them forward into their neutral positions.

In Figs. 25 to 27, the indicating element is in the form of a double shutter 50 having wings 50a, 50b (Fig. 27). The shutter is pivoted on pins 52 in a recess 55. A plunger 53 is provided for setting the indicating element 50 from its normal position, shown in full lines in Fig. 26, to its active position, shown in dotted lines. The end 15 of wing 50a has a V-shaped groove 54 for hooking on a latch spring 56 when in the active position. The shape of the recess 55 is such that in neutral position, the shutter wing 50a abuts against a shoulder 57 of the recess, as shown in Fig. 26, being biased to that position by a return spring 58, shown in Fig. 25. The sensing or identifying operation, to determine the position of shutter 50, may be performed either with a plunger like plunger 53, or with a plunger 59 entering through a side opening 60, as shown in Fig. 26.

Again, the sensing operation through the side opening 60 is preferred, since the plunger 59 then has no tendency to change the position of the indicating element. If the element 50 is in its normal position, the plunger 59 only pushes the wing 50a more tightly against the shoulder 57. If the element 50 has been set in its active position, with wing 50a latched by spring 56, then the plunger 59 will pass under wing 50b to the dotted line position of Fig. 26, without engaging the element 50.

The indicating elements 50 may all be set back to neutral by means of a vertical rod 61 having cam surfaces 62. When rod 61 is pushed downwardly, the cams 62 force the wings 50a out of engagement with the springs 56, so that the spring 58 returns the elements to their neutral positions.

The indicating elements 50 may have many forms other than those specifically described. It should be noted that in all the various modifications of indicating elements disclosed, the elements remain completely within their recesses at all times and so are protected against contact 40 with external objects which might change their indicating positions. Furthermore, in all the modifications, the positions of the indicating elements are not disturbed by the sensing operation.

In all the modifications, a difference in the position of 50 an indicating element produces a difference in the travel of a sensing tool, which difference in travel may be utilized to produce a control effect, as described in my copending applications mentioned above.

It is manifest that numerous mechanically equivalent 55 modifications may be introduced into the arrangements mentioned above and that numerous different forms of execution may be planned, without departing from the scope of the invention as defined in the accompanying claims.

60 I claim:

1. A settable indicator comprising a support having at least one outwardly opening recess, an indicating element completely within said recess and movable therein between at least two indicating positions, means in alignment with said opening for releasably retaining said element in any of its indicating positions, said element being observable from outside said recess in at least one of its indicating positions, and means partly blocking the outer end of the recess to prevent movement of the element therefrom and to protect said element against accidental movement between indicating positions by contact with external objects.

2. A settable indicator comprising a support having at least one outwardly opening recess, an indicating element completely within said recess and movable therein be-

tween at least two indicating positions, means for releasably retaining said element in any of its indicating positions, a sensing device insertable in said recess, said element being effective to modify the limit of travel of the sensing device into the recess in accordance with the position of the element, so that the sensing device travel indicates the element position, and means partly blocking the outer end of the recess to prevent movement of the element therefrom and to protect said element against accidental movement between indicating positions by contact with external objects.

3. A settable indicator comprising a support having at least one outwardly opening recess, an indicating element completely within said recess and movable therein in one sense between at least two indicating positions, means for releasably retaining said element in any of its indicating positions, a feeler movable into said recess in a sense different from the sense of movement of said element between its indicating positions, said element being effective to modify the limit of travel of the feeler into the recess in accordance with the indicating position of the element, so that the feeler travel indicates the element position, said feeler being ineffective to move the element from one indicating position to another because of the difference in said senses of movement, and means partly blocking the outer end of the recess to prevent movement of the element therefrom and to protect said element against accidental movement between indicating positions by contact with external objects.

4. A settable indicator comprising a support having at least one outwardly opening recess, an indicating element completely within said recess and movable therein between two indicating positions, means for releasably retaining said element in either of its indicating positions, a feeler insertable in said recess, said element being effective when in one only of said positions to modify the limit of travel of the feeler into the recess in accordance with the position of the element, so that the feeler travel indicates the element position, and means partly blocking the outer end of the recess to prevent movement of the element therefrom and to protect said element against accidental movement between indicating positions by contact with external objects.

5. A settable indicator comprising a support having at least one outwardly opening recess, an indicating element completely within said recess and rotatable therein between a plurality of different angular indicating positions, means for releasably retaining said element in any of its indicating positions, a sensing device insertable in said recess, said sensing device having an end surface complementary to the end surface of said element, said element being effective to modify the limit of travel of the sensing device into the recess depending upon whether the angular position of the sensing device end surface is in correspondence or non-correspondence with the angular position of the element, so that the sensing device travel indicates the element position, and means partly blocking the outer end of the recess to prevent movement of the element therefrom and to protect said element against accidental movement between indicating positions by contact with external objects.

6. A settable indicator comprising a support, at least one cylindrical outwardly opening recess in said support, a generally cylindrical indicating element completely within each said recess and rotatable therein, said element having on its outer end an index by which its angular position within said recess may be observed, and means in alignment with said opening for releasably retaining said element in at least two angular positions.

7. A settable indicator as defined in claim 6, wherein said retaining means comprises a non-circular portion at one end of said cylindrical element, and including stationary means for engaging said non-circular portion to prevent rotation thereof from either of said angular po-

sitions, said element being movable lengthwise of said recess out of engagement with said stationary means, and spring means engaging the opposite end of said element and biasing it into engagement with said stationary means.

8. A settable indicator as defined in claim 6, wherein said index comprises a transversely extending portion of said outer end terminating in a different plane than the remainder of said outer end, and said retaining means comprises a frusto-conical projection extending inwardly from the outer end of the recess and having its inner end formed to engage said transversely extending portion in different angular positions thereof to hold said index against rotation, and spring means engaging the inner end of said element and biasing it into engagement with said frusto-conical projection, said element being movable inwardly against said spring means to disengage said transversely extending portion from the frusto-conical projection so that the index may be rotated to change its angular position.

9. A settable indicator as defined in claim 6, wherein said index has a transverse rib at its outer end and said retaining means comprises a frusto-conical projection having its narrow end extending inwardly from the outer end of the recess and terminating in notches formed to receive said rib in different angular positions thereof, and spring means engaging the inner end of said element and biasing it into engagement with said frusto-conical projection, said element being movable inwardly against said spring means to disengage it from the frusto-conical projection so that it may be rotated.

10. A settable indicator comprising a support having at least one generally cylindrical aperture extending therethrough between front and rear surfaces thereof, a generally cylindrical indicating element rotatable within said aperture, and having a transverse rib on its front end which indicates the angular position of the element, front and rear plates respectively attached to the front and rear surfaces of said support, said front plate having an opening aligned with said aperture and smaller in diameter than said indicating element, so that the edge of the plate around the opening is effective to prevent movement of the element forwardly out of the aperture, said edge of the front plate being turned inwardly into said aperture and notched to receive said rib in a plurality of different angular indicating positions, and a spring on said rear plate engaging the rear end of said element and biasing said element forwardly to hold said rib in engagement with said notches, said spring and notches cooperating to retain said rib and element in any of said angular indicating positions, said element being rotatable by pushing it inwardly against said spring to disengage said rib from said notches.

11. A settable indicator as defined in claim 10, in which said indicating element has a generally conical rear end, and said spring is a leaf spring having a generally circular aperture aligned with the tip of said conical rear end, said apertured leaf spring cooperating with said conical rear end to center and guide said element.

12. A settable indicator as defined in claim 10, in which said notches extend only through the inturned portion of said edge, so that said rib cannot project beyond the outer surface of said front cover plate.

13. A settable indicator comprising a support having at least one generally cylindrical aperture extending therethrough between front and rear surfaces thereof, a generally cylindrical indicating element rotatable within said aperture, and having a transverse rib on its front end which indicates the angular position of the element, front and rear plates respectively attached to the front and rear surfaces of said support, said front plate having an opening aligned with said aperture and smaller in diameter than said indicating element, so that the edge of the plate around the opening is effective to prevent

movement of the element forwardly out of the aperture, said edge of the front plate being turned inwardly into said aperture and notched to receive said rib in a plurality of different angular indicating positions, and a spring on said rear plate engaging the rear end of said element and biasing said element forwardly to hold said rib in engagement with said notches, said spring and notches cooperating to retain said rib and element in any of said angular indicating positions, said element being rotatable by pushing it inwardly against said spring to disengage said rib from said notches, said element having a laterally extending portion on its front end, said recess having a front portion widened to receive said laterally extending portion, the rear wall of the front portion of said recess serving as a stop to limit the rearward movement of said element.

14. A portable indicating holder for articles, comprising side wall means and bottom wall means cooperating to form a pocket for receiving an article, one of said wall means having at least one outwardly opening recess, an indicating element completely within said recess, said element being movable in its recess between at least two indicating positions and observable from outside said pocket in at least one of said two positions, means for releasably retaining said element in any of its indicating positions, and means partly blocking the outer end of said recess to prevent movement of said element therefrom to protect said element against accidental movement between said indicating positions by contact with external objects.

15. A portable indicating holder for articles, comprising two relatively wide walls, two relatively narrow side walls between said wide walls, a bottom, said walls and said bottom cooperating to form a pocket for receiving an article, at least one of said side walls having at least one outwardly opening recess, an indicating element completely within said recess, said element being movable in its recess between at least two indicating positions and observable from outside said pocket in at least one of said two portions, means for releasably retaining said element in any of its indicating positions, and means partly blocking the outer end of said recess to prevent movement of said element therefrom, and to protect said element against accidental movement between said indicating positions by contact with external objects.

16. A portable indicating holder as defined in claim 15, said holder being stackable with others by placing the wide walls thereof together, said indicating element being observable when the holder is so stacked.

17. A portable indicating holder for articles, comprising two relatively wide walls, two relatively narrow side walls between said wide walls, a bottom, said walls and bottom cooperating to form a pocket for receiving an article, each of said side walls having at least one outwardly opening recess, an indicating element completely within said recess, said element being movable therein between at least two indicating positions and observable from outside said pocket in at least one of said positions, means for releasably retaining said element in any of its indicating positions, means partly blocking the outer end of said recess to prevent movement of said element therefrom and to protect said element against accidental movement between said indicating positions by contact with external objects, said holder being stackable with others by placing the wide walls thereof in contact, the indicating elements in both side walls being observable when the holder is so stacked with others.

18. A portable indicating holder for articles as defined in claim 17, in which said pocket is open at the top for receiving an article, and said bottom is openable to discharge an article from said pocket.

19. A portable indicating holder for articles as defined in claim 18, including means accessible through said open top for opening and closing said bottom.

20. A portable indicating holder for articles, comprising relatively wide front and rear walls, relatively narrow side walls between said wide walls, an openable bottom, said walls and said bottom cooperating to form a pocket for receiving an article, said rear wall being longer than the other walls and forming a projecting lower flange for supporting said pocket, at least one of said side walls having at least one outwardly opening recess, an indicating element completely within said recess, said element being movable in its recess between at least two indicating positions, means for releasably retaining said element in any of its indicating positions, and means partly blocking the outer end of said recess to prevent movement of said element therefrom, and to protect said element against accidental movement between said indicating positions by contact with external objects, said holder being stackable with others by placing the wide walls thereof together, said indicating element being observable in at least one of its positions and said bottom being openable when the holder is so stacked.

21. A portable indicating holder as defined in claim 20, in which said pocket has an open top which is accessible when the holder is stacked, and including spring means biasing said bottom closed, a pair of rods, one at each end of said pocket, said rods having their lower ends engaging said openable bottom and extending upwardly through said pocket with their upper ends accessible through said open top, said rods being pushable downwardly to open said bottom and frictionally engaged by the opened bottom to hold the rods in their downwardly displaced position.

22. A portable indicating holder as in claim 21, including lateral projections at the upper ends of said rods to facilitate an upward restoring movement thereof to allow said bottom to close.

23. A portable indicating holder for detached articles, comprising side wall means and bottom wall means cooperating to form a pocket open only at the top for receiving and carrying a detached article, one of said wall means having at least one outwardly opening recess, an indicating element within said recess, said element being movable in its recess between at least two indicating positions and observable from outside said pocket in at least one of said two positions, means for releasably retaining said element in any of its indicating positions.

24. A portable indicating holder for detached articles, comprising two relatively wide walls, two relatively narrow side walls between said wide walls, a bottom, said walls and bottom cooperating to form a pocket for receiving and carrying a detached article, said holder being stackable with other holders by placing the wide walls thereof in contact, each of said side walls having at least one outwardly opening recess, an indicating element within said recess, said element being movable therein between at least two indicating positions and observable from outside said pocket in at least one of said positions, means for releasably retaining said element in any of its indicating positions, said holder being stackable with others by placing the wide walls thereof in contact, the indicating elements in both side walls being observable when the holder is so stacked with others.
